UNITED STATES PATENT OFFICE

MARC RESEK, OF CLEVELAND HEIGHTS, OHIO, ASSIGNOR TO PERFECTION STOVE COMPANY, OF CLEVELAND, OHIO, A CORPORATION OF OHIO

STARTING BURNER FOR RETORT STOVES

Application filed December 3, 1926. Serial No. 152,356.

My present invention relates to a preheating or starting burner for stoves of the retort class wherein the lighter liquid hydrocarbons, such as gasoline, are used as fuel and are fed by air pressure.

Stoves wherewith this preheating or starting burner is especially adapted for use are shown in applications filed jointly by Lee S. Chadwick and myself as follows: Serial No. 10 126,366, filed August 2, 1926; Serial No. 149,353, filed November 19, 1926, and Serial No. 152,798, filed December 6th, 1926.

The fundamental purpose of this invention is to provide an efficient and reliable 15 so-called starting burner for preheating the retorts of stoves of the class referred to which utilizes the combustible mixture resulting from the injection of air under pressure into the fuel reservoir essentially for 20 the purpose of forcing the liquid fuel to the retort and burners. As a consequence of this arrangement, when it is desired to start the stove (assuming that air pressure prevails in the reservoir), it is only necessary to open 25 a valve in the connections between the air space of the reservoir and the starting burner and to apply a match or other lighting means to said burner and the carbureted air issuing therefrom will ignite to preheat 30 the retort and condition the stove for normal operation.

Another object is to adapt a starting burner of this nature to stoves employing removable fuel reservoirs; and, more specifically, to provide a construction involving 35 a single fluid-tight joint between the reservoir and a part of the stove structure to which the reservoir is detachably connected and through which part the conduits, 40 leading to the combustion device and starting burner, open into the reservoir.

Other objects are to provide a compact, simple and relatively inexpensive construction that is convenient of installation and 45 admits of ready disassembly for cleaning or replacement of parts should the same become necessary.

With these and other objects in view, the invention may be defined as consisting of 50 the combination and arrangement of parts

defined by the claims annexed hereto and illustrated in the accompanying drawings wherein Fig. 1 is a fragmentary sectional front elevation of a stove incorporating my improved starting burner; Fig. 2 is a plan view of the same with parts broken away to reveal certain connections; Fig. 3 is a sectional detail, in plan, and Fig 4, a sectional detail, as viewed from the front, of the connections between the fuel reservoir 55 and the pipe or conduit leading to the starting burner; Fig. 5 is a plan view of the starting burner and adjacent parts of the stove, and Fig. 6 is a section on the line 6—6 of Fig. 5.

The stove structure comprises a top 1, legs 2 that support the top a suitable distance above the floor, end panels 3 and 4 that extend from the front to the rear legs at the opposite ends of the stove, and a burner pan 5 that is supported a suitable distance below and parallel with the top 1.

A manifold 6 is supported within the space between the top 1 and the burner pan 5 by brackets 7 that are carried by and extend inwardly from the end panels 3 and 4 and have their inner ends suitably secured to the ends of the manifold. Burners 10 and 11 surmount the opposite ends of the manifold 6 and are located beneath 75 openings 12 in the stove top. Rising from about the longitudinal center of, and preferably formed integral with, the manifold 6 is a mixer 15 whose outer end is turned toward the burner 10, and the same is formed with an end wall 16 which shields the downwardly directed inlet end of the mixer from the direct heat of the burner flame.

Secured to the outer side of the end panel 4 in about the plane of the pan 5 is a unit 18 that is in the form of a substantial casting and to which is adapted to be removably attached a fuel reservoir 19. Rising from the inner end of the unit 18 is a fuel pipe or conduit 20 that includes a valve 21 and connects at its upper end with a tubular retort 22 that is projected through an aperture in the panel 4 and across the burner 10 and has its inner end projected through a

hole in the end wall 16 of the mixer 15. This retort is detailed in the aforesaid application Serial No. 152,356. A valve at the inner end of the retort is controlled by a hand wheel 23 that is applied to the outer end of the valve stem 24.

As best illustrated in Figs. 3 and 4, the outer end of the unit 18 is formed with a depending boss 25 that is surrounded by an annular seat 26, and a tube 27 projects axially from the boss 25. The reservoir 19 has a neck 30 that is adapted to be engaged over the boss 25 and bear, at its upper end, against a gasket 31 that is applied to the seat 26. Pivottally connected at 32 to diametrically opposite parts of a band 33 that is clamped about the neck 30, are the ends of a yoke 35 through the central portion of which a screw 36 is threaded for engagement with a depressed abutment 37 formed on the unit 18 directly above the boss 25. This screw 36, equipped as it is with a knob 38, forms a handle for carrying the reservoir when the same is detached from the stove. By means of the screw 36 the reservoir may be drawn up with its neck forced tightly against the gasket 31 thereby to effect a fluid-tight joint between the reservoir and the unit 18.

30 A passageway 40 in the unit 18 connects at one end with the tube 27 and at the other with the pipe or conduit 20. Air is adapted to be introduced into the reservoir through a passageway 41 which opens at one end 33 through the bottom of the boss 25 and at the other through a pump fitting 42 that involves a valve, all of which is detailed in a co-pending application of Lee S. Chadwick, Serial No. 160,846, filed January 13, 1927. It may be explained in passing that the air pump that is designed for use with this outfit has a hexagonal outlet extension that is adapted to be placed within the fitting 42 so that by turning the pump in one direction the screw valve incorporated in the fitting may be opened and, by turning it in the opposite direction the valve may be tightly closed.

45 designates another passageway that 50 opens at one end through the bottom of the boss 25 and at its opposite end through the inner end of the unit 18 in register with an opening 46 in the end panel 4, and passage of fluid through the same is controlled by a valve 47 that cooperates with a seat 46 which surrounds the passageway at the inner end of a threaded enlargement within which the threaded portion 48 of the valve stem 49 operates. The outer end of the stem is 55 equipped with an operating key or handle 50. Conveniently located on the rear side of the unit 18, opposite the pump connection previously referred to, is an air gauge 55 that communicates through a connection 56 60 with the passageway 45. The air gauge is

constantly subjected to any air pressure within the reservoir through the passageway 45. The end of the passageway 45 adjacent the inner end of the unit 18 is counterbored and tapped to two different depths 70 for the reception of the threaded inner end of a nozzle 58 and the threaded end of an elbow fitting 59, said fitting having an air inlet 60 so as to constitute of the fitting a mixer for supplying secondary air to the 75 gaseous mixture that issues from the orifice 61 of the nozzle 58 when the valve 47 is opened. A tube 65 leads from the fitting 59 to an elbow fitting 66 that is threaded 80 into a bushing 67 which, in turn, is threaded into the rear end of a cylindrical portion 68 of the starting burner head designated generally by the reference character 70. The burner head incorporates an attaching plate 71 that is adapted to be secured, by a screw 72, to the end wall 16 of the mixer 15, and said attaching plate is provided with a hole through which the inner end of the retort 22 is extended. The burner head is 85 also provided with a hood 74 which extends over the adjacent end of the retort and serves to confine the flame of the starting burner in effective relation to the retort. The inner end of the cylindrical portion 68 is contracted slightly about an opening 75 thereby to provide an internal shoulder 90 against which the peripheral portion of a burner screen 76 is adapted to be clamped by a sleeve 77 that is held in place by the 95 previously mentioned bushing 67.

100 Preparatory to starting the stove in operation, and with all valves closed, an air pump (not shown) is applied to the fitting 42 and rotated in a direction to open the valve incorporated in said fitting and the pump is 105 actuated to force air through the passageway 41 into the reservoir 19. When the desired air pressure has been created within the reservoir as indicated by the gauge 55, the pump is turned in the opposite direction 110 to close the aforesaid valve. This feature constitutes no part of my invention and for that reason is not illustrated, though details of the same may be had by reference to the aforesaid application Serial No. 160, 115 846. The air confined within the reservoir becomes carbureted in the presence of the liquid fuel and upon opening the valve 47 by the manipulation of its operating handle 120 50 the carbureted air issues from the orifice 61 of the nozzle 58 and, mixing with air admitted through the opening 60 of the fitting 59, passes on through tube 65 to the starting burner where it may be ignited by the application of a match or other lighting 125 means to the region of the opening 75. The screen 76, functioning in the manner of the usual burner screen, controls the mixture in such a way as to cause the same to burn with a blue flame about the inner end of 130

the retort 22, the hood 74 deflecting the blaze along the retort for a material distance. When the retort is heated to the temperature required to generate gas, liquid fuel is admitted to the retort by opening the valve 21 and with the previously mentioned valve that is situated at the inner end of the retort open the gas issues from the retort into the mixer 15, where it commingles with air admitted through the open end of the mixer, and passes on through the manifold 6 to the burner 10 where it may be ignited from the flame of the starting burner, after which the starting burner may be shut off by closing the valve 47. The burner 11 that is connected with the end of the manifold 6 opposite the burner 10 is controlled by a valve which may be of any approved character and the operating handle of which is designated 80.

Having thus described my invention, what I claim is:—

1. A starting burner for use with a combustion device having a retort, said starting burner consisting of a self-contained unit comprising a hollow body provided with a gas emitting opening, means for supplying gas to said body, a hood projecting from the body over and beyond the aforesaid opening, and means on the body for positioning the retort of the combustion device in operative relation to said hood and opening so that the flame of the burner is diverted about and along the retort.

2. A starting burner for use with a combustion device having a retort, said starting burner consisting of a self-contained unit comprising a hollow cylindrical body having a gas emitting opening, an attaching plate formed integral with the body and extending along one side thereof and beyond the gas emitting opening, and a hood projecting from the body over and beyond the gas emitting opening and joined at one side to the attaching plate, the attaching plate being formed to cooperate with and position the retort of the combustion device beneath the hood and in such relation to the gas emitting opening as to cause the flame of the starting burner to be diverted about and along the retort.

3. A starting burner consisting of an integral unit incorporating a hollow cylindrical portion having a gas emitting opening at one end, an attaching plate extending along one side of the cylindrical portion and beyond the end thereof that is provided with said opening, and a hood projecting from said cylindrical portion over and beyond the gas emitting opening, said attaching plate having an aperture for receiving a retort and locating it in operative relation to the gas emitting opening.

4. A starting burner comprising an integral body incorporating a hollow cylindri-

cal portion having a gas emitting opening at one end surrounded by an internal shoulder, an attaching plate extending along one side of the cylindrical portion and beyond the end thereof that is provided with said opening, and a hood projecting from said cylindrical portion over and beyond the gas emitting opening, said attaching plate having an aperture for receiving a retort and locating it in operative relation to the gas emitting opening, a screen disposed across the gas emitting opening and having its peripheral portion engaging the aforesaid shoulder, a sleeve fitted within said cylindrical portion and having one of its ends 70 engaging the peripheral portion of the screen in opposed relation to the shoulder, and a pipe connection screwed into the opposite end of said cylindrical portion and having its inner end engaging the adjacent 75 end of said sleeve.

In testimony whereof, I hereunto affix my signature.
